CLAIM

The ornamental design for a display screen or portion thereof with graphical user interface, as shown and described.

DESCRIPTION

FIG. 1 is a front view of a graphical user interface for a display screen or portion thereof showing a first image in a sequence of images according to an embodiment of our new design;

FIG. 2 is a front view of a graphical user interface for a display screen or portion thereof showing a second image in the sequence of images according to the embodiment of FIG. 1; and,

FIG. 3 is a front view of a graphical user interface for a display screen or portion thereof showing a third image in the sequence of images according to the embodiment of FIG. 1.

The broken lines show portions of the display screen or portion thereof which form no part of the claimed design. The appearance of the transitional image sequentially transitions between the images shown in FIGS. 1-3. The process or period in which one image transitions to another image forms no part of the claimed design.
